UNITED STATES PATENT OFFICE.

JOHN A. WILSON, OF COLUMBUS, KANSAS.

BEDSTEAD.

1,036,016.

Specification of Letters Patent. Patented May 14, 1912.

Application filed July 1, 1911. Serial No. 636,376.

To all whom it may concern:

Be it known that I, JOHN A. WILSON, a citizen of the United States, residing at Columbus, in the county of Cherokee and State of Kansas, have invented new and useful Improvements in Bedsteads, of which the following is a specification.

The general object of the invention is to provide a bed that may be knocked down and folded into a comparatively small compass when not in use.

Other objects will appear and be better understood from the following description taken in connection with the accompanying drawings, in which,

Figure 1 is a side elevation. Fig. 2 is an end elevation of the head end of the bed. Fig. 3 is a detail perspective of one end portion of the bed showing means for locking the spring against displacement. Fig. 4 is a sectional detail showing the means for locking the spring. Fig. 5 is a detail perspective of one end portion of the stay bar showing the same connected to one of the supporting legs. Fig. 6 is a front elevation of one end portion of the stay bar shown in Fig. 1 but with the leg removed. Fig. 7 is a detail side elevation with the parts partly folded. Fig. 8 is a similar view of the parts completely folded.

The side rails *a* and end rails *b* are preferably though not necessarily formed of metal and are herein shown as right angular in cross sectional contour but it must be understood that I am not to be limited to the specific use of metal or the cross sectional contour shown and described since these details may be varied if desired and are herein shown and described merely to enable those skilled in the art to clearly understand one embodiment of the invention.

In order that the bed may be readily folded or collapsed I form the side rails *a* in sections 5 and 6, the said section of each rail may be connected together in any preferred manner such as by a rule-joint 7 and the sections of each rail may be further connected to the end rails *b* in any preferred manner such as by pivot pins 8. The sections 5 and 6 of each rail are adapted to fold one upon the other as shown in Fig. 7 and when so adjusted the head and the end rails will bear one upon the other whereupon the side rails may be folded one upon the other and on to the end rails. In this connection it will be observed that the sec-

tions comprising the side and end rails are of uniform size in cross section, and also the sections 5 and 6 move in a direction when folding one upon the other at right angles to the direction in which the side rails move when folding one upon the other and on to the end rails. It will be also observed that the side rails are of different lengths and at the juncture of the side and end rails angular shaped brackets 9 are provided which are herein shown as secured to the end rails and connected by the pivots 8, before stated, to the side rails. It will be observed that the brackets connecting the shorter side rail with the end rails are longer than the opposite brackets connecting the longer side rail, the length of the longer brackets being sufficient to permit the shorter side rail to be folded on to the longer when the latter is folded on to the end rails as shown in Fig. 8.

The supporting legs *c* are arranged at the opposite ends and middle portion of the bed, the legs 10 at the foot end of the bed being herein shown as angular in cross section and pivoted to the foot rail and foldable on to the latter. Suitable latches 11 are pivoted to the legs 10 and are adapted to interlock with keepers 12 and coöperate with the same to hold the legs 10 against movement when the bed is set up and ready for use.

The middle legs 13 are herein shown as angular and pivoted to and adapted to be folded on to the side rails. Suitable latches 14 carried by one of the sections of the side rails are adapted to interlock with keepers 15 on the legs 13 and serve to prevent movement of the latter when the bed is set up as previously described. The bed at its middle portion is braced and the strain taken from the joints of the side sections by means of a suitable stay which is herein shown to include a bar 16 adapted to interlock with the middle legs 13 this interlocking connection between the bar 16 and legs 13 being accomplished in any suitable manner such as by studs 17 arranged at the opposite ends of the bar 16 and adapted to enter openings in the legs 13. Suitable stops 18 are arranged on the bar 16 and adapted to bear on the adjacent edges of the legs 13, and latches 19 are herein shown as pivoted to the stops 18 and movable over one face of the legs 13 when the bar is connected thereto whereby to prevent accidental displacement of the bar.

- The legs 20 at the head end of the bed are herein shown as pivotally connected to and adapted to fold on to the head rail when the bed has been folded as previously described.
- 5 In order to prevent folding of the legs when the bed is set up I make use of a head-piece herein shown to consist of depending portions 21 connected at their upper ends by a cross-piece 22 and having offset portions 23 at their lower ends provided with studs 24 received by bayonet slots 25 in the legs 20. The cross-bar 22 is pivoted to the portions 21 whereby the latter may be folded on to the former when not in use.
- 10 The portions 21 are adapted to interlock with the head rail in any preferred manner such as by means of studs having shank portions 26 adapted to enter notches 27 in the head rail, the cross-piece 22 is also
- 15 adapted to interlock with the head rail in any preferred manner such as by means of a latch 28 adapted to engage a keeper 29 carried by the head rail.
- It will be observed that the legs are
- 20 formed with shoulders 30 which bear on the side and end rails whereby the weight of the parts is not thrown on to the pivots of the legs.
- In connection with the bed just described
- 25 I make use of the spring 31. The body of this element comprises a plurality of links 32 arranged end to end and connected by eyes 33 the eyes being in turn connected by cross-links 34. The body is connected to
- 30 the end bars 35 and 36 by means of retractile springs 37 and the bars 35 and 36 are adapted to interlock with hooks 38 and 39 secured to the end rails as shown. The bars 35 and 36 have recesses 40 which receive the bills of the hooks 38 and 39 and the said bars are herein shown as corresponding substantially in width to the horizontal side portions of the end rails so that in order to connect the bars with the hooks
- 35 it is necessary to slightly tilt the same in order that the bills of the hooks may enter the recesses of the bars. In order to prevent accidental engagement between the bars and hooks I make use of a locking device one embodiment of which is herein shown to consist of levers 42 pivoted to the end rails and adapted to be moved outwardly and under clips 43 carried by the bars 35 and 36 after engagement between
- 40 the latter and the hooks has been effected.
- 45 With this construction it will be seen that when the levers and clips bear one upon the other it will be impossible to tilt the bars sufficiently to disengage the same from the
- 50 hooks.
- The spring previously described is somewhat less in length than the distance between the hooks at the opposite end rails and one method of tensioning the spring
- 55 consists in first connecting one of the bars
- with the hooks of one end rail and then partly folding the side rails so as to bring the hooks of the opposite end rail nearer to the hooks of the first named end rail in which position the other bar may be readily
- 60 connected to the hooks and lock as previously described, after which the sections may be moved into alignment whereupon the spring will be tensioned.
- Assuming that the bed has been set up
- 65 and it is desired to fold the same the head-piece is first removed by disengaging the latch 28 with the keeper 29, after which the head-piece is moved upwardly in the bayonet slots 25 until the portions 21 may be
- 70 moved inwardly and out of engagement with the side slots whereupon the head-piece may be removed. The latches 14 are then disengaged from the middle legs 13 whereupon the sections of the side rails may be
- 75 partly folded thus removing the tension on the spring and permitting the same to be detached from the hooks which may be accomplished first by moving the levers 42 from engagement with the members 43.
- 80 When the spring has been removed the sections 5 and 6 of each side rail are folded one upon the other, after which the legs are folded on to the side and end rails, it being understood that the latches of the
- 85 foot end legs are first disengaged from their keepers. When this has been done the parts will be positioned as shown in Fig. 7 after which the side rails may be folded one upon the other as previously described whereupon the entire structure when folded will be of no greater length than one of the end rails.
- 90 By virtue of the flexibility of the spring the latter may be wrapped around the folded bed and the whole packed into a
- 95 small box or receptacle.
- From the foregoing it will be seen that the device is exceedingly simple in structure and has a minimum of parts and is particularly adapted for use in camps, households, etc.
- 100 Although I have shown and described one form of the device it is to be understood that I am not to be limited to this specific structure and arrangement of parts since
- 105 various changes may be made, in the scope of the appended claims without departing from the spirit or sacrificing any of the advantages of the invention.
- 110 What I claim as new is:
1. In a collapsible bed, the combination of end rails, side rails including pivotally connected sections pivoted to the end rails, each of said side sections being foldable one upon the other and also foldable parallel to
- 115 the end rails.
2. In a collapsible bed, the combination of end rails, side rails including pivotally connected sections pivoted to the end rails,
- 120 said side rails being foldable one upon the
- 125

other and also foldable onto and parallel with the end rails.

3. In a collapsible bed, the combination of end rails, side rails including pivotally connected sections pivoted to the end rails, said side rails being foldable one upon the other and also foldable onto and parallel with the end rails, and supporting legs pivotally connected to said side and end rails 10 and foldable thereonto.

4. In a collapsible bed, the combination of the end rails, hooks carried thereby, a

spring having end bars to engage said hooks and coöperating devices carried by the end rails and end bars and adapted for locking 15 the end bars against displacement from said hooks.

In testimony whereof I affix my signature in presence of two witnesses.

J. A. WILSON.
